UNITED STATES PATENT OFFICE.

PAUL H. HAMILTON, OF CLEVELAND, OHIO, ASSIGNOR TO THE SANDS MANUFACTURING COMPANY, OF CLEVELAND, OHIO, A CORPORATION OF OHIO.

DESIGN FOR A HEATER.

Application filed March 25, 1927. Serial No. 21,346. Term of patent 14 years.

To all whom it may concern:

Be it known that I, PAUL H. HAMILTON, a citizen of the United States, residing at Cleveland, in the county of Cuyahoga and State of Ohio, have invented a new, original, and ornamental Design for Heaters, of which the following is a specification, reference being had to the accompanying drawing, forming part thereof.

Fig. 1 is a side elevation of a heater, showing my new design.

Fig. 2 is a plan view thereof.

I claim:

The ornamental design for a heater, as shown.

PAUL H. HAMILTON.
